UNITED STATES PATENT OFFICE

123,185

DESIGN FOR A DRAFT REGULATOR FOR FURNACES

William C. De Roo, Holland, Mich., assignor to
Hart & Cooley Manufacturing Company, Hol-
land, Mich., a corporation of Delaware

Application August 22, 1940, Serial No. 94,570

Term of patent 14 years

To all whom it may concern:

Be it known that I, William C. De Roo, a citizen
of the United States, residing at Holland, in the
county of Ottawa and State of Michigan, have
invented a new, original, and ornamental Design
for a Draft Regulator for Furnaces, of which the
following is a specification, reference being had to
the accompanying drawing, forming part thereof.

Fig. 1 is a front elevational view of a draft

regulator for furnaces, showing my new design.

Fig. 2 is an end elevational view of the same.

Fig. 3 is a plan view of the same, and

Fig. 4 is a perspective view of the same.

I claim:

The ornamental design for a draft regulator
for furnaces, as shown.

WILLIAM C. DE ROO.
